(57) **CLAIM**

The ornamental design for a hanging storage bag, as shown and described.

DESCRIPTION

FIG. 1 is a perspective view of a hanging storage bag showing my new design;

FIG. 2 is a front view thereof;

FIG. 3 is a rear side view thereof;

FIG. 4 is a left side view thereof;

FIG. 5 is a right side view thereof;

FIG. 6 is a top view thereof; and,

FIG. 7 is a bottom view thereof.

The broken lines depicting portions of the hanging storage bag form no part of the claimed design.
